CLAIM

The ornamental design for a tool storage assembly, as shown and described.

DESCRIPTION

FIG. 1 is a front perspective view of the tool storage assembly;

FIG. 2 is a top view thereof;

FIG. 3 is a bottom view thereof;

FIG. 4 is a front view thereof;

FIG. 5 is a side view thereof; and

FIG. 6 is an opposed side view thereof; and,

FIG. 7 is a rear perspective view thereof.

The broken line portions of the figure drawings are included to show unclaimed subject matter and form no part of the claimed design.

1 Claim, 2 Drawing Sheets(56)
